UNITED STATES PATENT OFFICE.

JOHN E. CARLSON AND WALTER G. NORDMAN, OF ELKHART, INDIANA.

CLOSURE STRUCTURE.

Application filed August 10, 1926. Serial No. 128,422.

This invention relates to an improved device which may be referred to conveniently as a closure structure, the same being adapted more particularly to take the place of a 5 window such as is used in a cellar of a domestic home to accommodate placement of coal and the like therein.

The invention, however, is not to be restricted to this purpose, since it is equally 10 well usable as a closure for openings commonly known as chicken holes in a chicken coop, and also as a closure for an opening in an animal enclosure or pen.

Our primary aim is to provide a structure 15 of this kind wherein the closing element itself is swingably mounted and means is provided for operating it at a distant point. For instance, where the device is used as a closure for a window opening in a cellar 20 to which coal is usually placed, we propose to provide operating chains or the like extending into the interior of a room in proximity to the particular openings, whereby the closure may be placed in the opening and 25 then closed, thus obviating the necessity of going into the cellar to manipulate the closure, and thereby avoiding contact with coal dust and dirt.

Of course, another object is to provide a 30 structure of this kind comparatively simple in construction, such as to permit it to be easily installed, one which includes practical details arranged in a novel association, and a device which is altogether efficient in accomplishing the result itself.

Other features and advantages of the invention will become apparent from the following description and drawings.

In the accompanying drawings forming a 40 part of this application and in which like numerals are employed to designate like parts throughout the same:—

Figure 1 is a view in section and elevation of a closure showing the same installed 45 in a building wall,

Fig. 2 is a horizontal section taken approximately upon the plane of the line 2—2 of Fig. 1,

Fig. 3 is a central vertical section showing 50 the internal construction more plainly,

Fig. 4 is a transverse vertical section thru one end portion of the structure, showing the latch mechanism plainly,

Fig. 5 is a view like Fig. 4, taken on a different line and approximately through the 55 center of the structure,

Fig. 6 is a perspective view of one of the details, and

Fig. 7 is a perspective view of another one 60 of the details.

Referring to the drawings in detail, it will be seen that the reference character 1 designates generally a substantially rectangular casing. This casing is simply made up of inner and outer walls 2 and 3 connected together partly by pins 4, the pins being disposed slightly inwardly of the marginal edges of the wall. These walls or plates are provided at their center with oppositely disposed rectangular openings having inwardly struck flanges 5 formed around the margin thereof.

Cooperating with the flanges is a rectangular sleeve 6 forming a smooth surface opening to provide the desired entrance. 75 This entrance is closed on one side by the closure proper, generally designated by the reference character 7. The closure comprises an inner plate 8, an outer plate 9, and a central glass window 10, the plates being 80 secured to each other and the window being confined therebetween.

The plates are provided with slots disposed opposite each other to permit passage of light whereby the closure may function 85 as a window. As shown in Fig. 1, this closure is fastened as at 11 to a rock shaft 12 journaled for rotation in bearings formed in segmental boxings 13 at the ends of a special shield 14. This shield is provided with marginal attaching flanges 15 and 16 and it constitutes a housing for the shaft and connection of the closure. One purpose of the housing is to prevent accumulation of dust and dirt on the parts, and to add to the 90 general attractive appearance of the structure.

Carried by the rock shaft and shown plainly in Figs. 4 and 5, are crank arms 17 which are bowed somewhat and which are 100 in turn connected to the bifurcated portion of counter-balancing weights 18. With this arrangement the weights normally move the crank arms downwardly and rock the shaft 12 in a manner to lift the closure 7 upwardly to open position. Novel means is, however, provided for automatically rocking and retaining the closure in closed position. The means referred to comprises a novel latch 19 as shown in Fig. 6. This latch is 110 of the form of a casting which is pivoted between its center at 20 in Fig. 3.

One end portion is bifurcated as indicated at 21. Also the opposite end is bifurcated and the furcations are somewhat longer. One of the furcations, designated by the reference character 22 is constructed with an angularly disposed end portion 23 terminating in an upwardly directed latch 24. The portion 23 extends through a slot 25 (see Fig. 3) in the outer plate 3. This arrangement permits the latch 24 to be engaged with the bottom of the closure as shown plainly in Fig. 5, for holding the closure in closed position. By preference, complementary stampings 26 and 27 are formulated to provide an enclosure about this latch to prevent passage of dirt and dust.

It is obvious of course, that the latch is counter-balanced owing to the heavy end portion 21. A pin is fastened to this end portion between the furcations, and a pull chain 28 is connected with the pin and extends upwardly through a guide 29, and the interior of the casing structure.

A complementary chain 30 is connected with one of the aforesaid weights 18 as shown better in Fig. 5. Both of these chains have finger rings 31 at their upper ends located in a wall box 32. This box is located at a suitable point in the room and is provided with an appropriate sliding closure 33.

The device may be located in the wall 34 as shown in Fig. 2 and the chains 28 and 30 will be extended up between the walls of 35 the dwelling and the finger rings located in the wall boxes or a single box as shown. The cover plate will serve to hide the box so as to dispose it out of sight. The latch 24 is engaged with the swingable closure as 40 represented in Fig. 5, and if it is desired to swing the closure to open position, it is only necessary to grasp the pull chain 28 and lift upwardly on the same, thus overbalancing the weighted end of the latch 19, and 45 disengaging the latch 24 from the closure.

The moment that the latch is disengaged, the rock shaft 12 will swing downwardly under the action of the weights 18, thus moving the closure to open position. In order 50 to close the same, it is necessary to pull upwardly on the other chain 30, thus lifting the weights and swinging the closure downwardly. As the closure moves in this direction, the gravity actuated latch will 55 automatically engage the same and hold it closed in an obvious manner.

It is believed that the construction and advantages of the device will be clear from a careful consideration of the drawing and description. Therefore, a more lengthy 60 description is thought unnecessary.

While the preferred embodiment of the invention has been shown and described, it is to be understood that minor changes coming within the field of invention claimed 65 may be resorted to if desired.

Having thus described our invention, what we claim as new is:—

1. In a window closure of the class described, a casing of hollow form constructed 70 to fit in a cellar window opening, said casing being provided with an entrance opening, a closure for said entrance opening, an oscillatory rock shaft with which said closure is rigidly connected for upward 75 swinging motion, bearings on the casing in which said rock shaft is journaled for oscillation, a latch pivotally mounted in the casing for holding the closure in closed position, crank arms connected with said rock 80 shaft and confined in said casing, and counter balanced weights connected with and depending from said crank arm, whereby when the latch is released the closure will be automatically swung to open position 85 through the action of the counterbalanced weight.

2. In a cellar window construction of the class described, a hollow casing constructed to fit in a cellar window opening, 90 said casing being provided with an entrance opening and having external bearings, a rock shaft mounted for oscillation in said bearings, a closure rigidly connecting said rock shaft and swingable over said entrance 95 opening, a shield over said bearing and shaft for concealing said parts, crank arms connected to the rock shaft and confined within said casing, counter weights pivotally connected to and depending from the crank 100 arm, a body pivotally mounted in the casing and including a latch cooperable with said closure for holding the closure in closed position, a pull chain connected with said body and adapted to extend to a distant point, 105 and wall box with which the free end portion of the pull chain is adapted to be associated.

In testimony whereof we affix our signatures.

JOHN E. CARLSON.
WALTER G. NORDMAN.
